[57] CLAIM

The ornamental design for a keyboard, as shown and described.

DESCRIPTION

FIG. 1 is a top perspective view from the lower right-hand corner of a keyboard showing my new design with the legs in an extended position;

FIG. 2 is a top perspective view from the upper left-hand corner of the keyboard with the legs in an extended position;

FIG. 3 is a top view of the keyboard;

FIG. 4 is a front view of the keyboard with the legs in an extended position;

FIG. 5 is a rear view of the keyboard with the legs in an extended position;

FIG. 6 is a left side view of the keyboard with the legs in an extended position;

FIG. 7 is a right side view of the keyboard with the legs in an extended position;

FIG. 8 is a bottom perspective view from the right hand top corner of the keyboard with the legs in an extended position;

FIG. 9 is a top perspective view from the lower right-hand corner of a keyboard with the legs in a retracted position;

FIG. 10 is a top perspective view from the upper left-hand corner of the keyboard with the legs in a retracted position;

FIG. 11 is a bottom perspective view from the right hand top corner of the keyboard with the legs in a retracted position.

The outlines of the keys on the keyboard are shown in broken line in FIGS. 1, 2, 3, 4, 9 and 10 for illustrative purposes only.
